[57] CLAIM

The ornamental design for a lavatory, as shown and described.

DESCRIPTION

FIG. 1 is a perspective view taken from the top, front and left side of a lavatory embodying our new design;

FIG. 2 is a front elevational view thereof;

FIG. 3 is a right side elevational view thereof, the left side being the mirror image thereof shown;

FIG. 4 is a rear elevational view thereof;

FIG. 5 is a bottom plan view thereof;

FIG. 6 is a perspective view taken from the top, front and left side of a second embodiment of our new design, which is the same as the embodiment of FIG. 1 except for the addition of a second cross member on each pair of legs;

FIG. 7 is a top plan view of both of the embodiments of FIGS. 1 and 6;

FIG. 8 is a cross-sectional view, taken on line 8—8 of FIG. 7, of the sink portion above the legs; and,

FIG. 9 is a cross-sectional view, taken on line 9—9 of FIG. 7, of the sink portion above the legs.

The broken line representations of mounting holes in FIGS. 1, 6 and 7 are for the purpose of illustration only and form no part of the claimed design.

The bottom view of the second embodiment is identical to that shown in FIG. 5.
